UNITED STATES PATENT OFFICE.

JOSEF BRANDSTETTER, OF ROCHESTER, MINNESOTA, ASSIGNOR TO SEARS, ROEBUCK & COMPANY, OF CHICAGO, ILLINOIS, A CORPORATION OF NEW YORK.

SOUND-BOX.

1,307,236.

Specification of Letters Patent. Patented June 17, 1919.

Application filed February 21, 1917. Serial No. 150,188.

To all whom it may concern:

Be it known that I, JOSEF BRANDSTETTER, a subject of the Emperor of Austria-Hungary, residing at Rochester, in the county 5 of Olmsted and State of Minnesota, have invented certain new and useful Improvements in Sound-Boxes, of which the following is a specification, reference being had therein to the accompanying drawing.

10 My invention relates to sound recording and reproducing or so called "talking" machines and has for its object the improvement of sound boxes used therewith.

An object of my invention is to provide 15 a sound box with improved means for tensioning the stylus lever and its bearings, whereby the bearings may be kept under sufficient tension to prevent chattering, and at the same time maintain ample flexibility 20 in the tensioning of the said lever to prevent over-damping of its vibrations of high amplitude.

Another object of my invention is to provide 25 a symmetrical means for tensioning both the bearings and the stylus lever, arranged to automatically maintain a substantially constant ratio between the tension on the bearings and the tension on the said stylus lever throughout various adjustments, 30 and also to act always in the plane in which the stylus lever vibrates, and perpendicularly to the axis around which said lever vibrates.

Other objects of my invention reside in 35 the novel construction, combination and arrangement of parts hereinafter described and particularly pointed out in the appended claims.

40 My invention is illustrated in the accompanying drawings in which

Figure 1 is a front elevation of my improved sound box.

Fig. 2 is a side elevation of the same partly in transverse section.

45 Fig. 3 is a bottom plan view with the stylus set screw removed.

Fig. 4 is a bottom plan view of the bearing yoke carrying the stylus lever.

50 Figs. 5 and 6 are detail views of one of the tensioning springs.

Referring to the drawings in detail, 1 indicates the body portion of the sound box proper consisting of the annular side wall 2, back wall 3, and flange or neck portion 4.

55 A flat surfaced mounting lug 5 is formed

on the lower edge of the sound box body and has a pair of knife edges 6 and 7 secured thereto. The diaphragm 8 of mica or other equivalent material is suitably mounted within the sound box, as between 60 a pair of tubular rubber gaskets 9 and 10, the inner gasket 9 being partially countersunk or nested into an annular recess 11 in the back wall 3 of the sound box body. These gaskets are held in place and compressed as shown in Fig. 2 by means of the retaining ring 12 threaded on its periphery to engage complementary threads at 13 on the inner surface of the annular side wall 2, the proportions of the diaphragm and sound 65 box cavity being such that, when the ring 12 is screwed in flush with the front surface of the sound box, the gaskets will be compressed to hold the diaphragm resiliently and without lost motion therebetween, 70 spaced away from the back wall of the sound box and with a slight clearance between the periphery of the diaphragm and the side wall of the sound box at 14. As an alternative construction, the ring 12 may be laid 75 flat on or within the edge flange of the box and screws tapped through it into the body of the box. This is in some respects a preferred construction, as by using a number of screws around the ring, it enables adjustment to be made of the pressure on different parts of the gaskets and diaphragm. A stylus lever 15 connected to the diaphragm 80 at 16 is carried by the bearing yoke 17 which is provided with a shallow trough or depression 85 at each end, 19 and 20, in which seat the knife edges 6 and 7 respectively. The bearing yoke 17 carries a pair of tensioning arms 21-22 extending at right angles therefrom in opposite directions and in the longitudinal plane of the stylus lever; and extending downwardly from the yoke and positioned centrally thereof is a stylus holder 23 which is provided with the usual socket 90 24 and knurled set screw 25 for holding the stylus point 26, the parts being so arranged 95 as to bring the stylus point approximately in the line of intersection of the perpendicular planes passing through the diaphragm and the stylus lever.

100 For holding the knife edge bearings seated and tensioning the stylus lever, I provide a pair of bow springs 28 and 29 secured and tensioned by adjusting screws 27 and 31 respectively, threaded into the mounting lug 110

5. These springs are arranged with relatively short and long fingers 30—32 and 33—34, which respectively bear on the ends of the yoke directly under the knife edges 5 and on the ends of the tensioning arms 32 and 29. In order to prevent these tensioning springs from turning about the adjusting screws, I provide the ends of the tensioning arms with downwardly projecting pins 10 which pass through holes or slots 35—36 in the ends of the long fingers of the springs. Between the ends of each spring finger and the point where it engages its yoke or tensioning arm, I place a small contact pad, 15 37—38, of suitable resilient material such as rubber, the pads 37 being held in place by small indentations 39 in the ends of the yoke into which a portion of the pad extends under pressure of the spring, and the pads 38 being held in place by means of the downwardly projecting pins which pass through the slots 35—36. A sharp bend or dip 40 is formed at the end of each spring 20 at the point of engagement with the pad to reduce the area of the contacting surface to a narrow zone running transversely of the spring so as to permit a slight rocking motion between the ends of the spring fingers and the pads without substantially varying the 25 leverage of the spring fingers. It will be readily seen from the drawings that the tension of the springs can be accurately adjusted by means of the screws 27—31, which may be set at any adjustment by means of 30 the lock-nuts 41—42.

By the arrangement of the tensioning springs as here shown and described, the same set of springs is used both for holding the bearings firmly seated and for tensioning the stylus lever, at the same time affording a sufficient pressure on the bearings to prevent their chattering without exerting an undue pressure on the stylus lever. I obtain this difference in pressure between 40 the different ends of the same springs by making the springs with long and short fingers as shown in Fig. 3 and arranging them so that the short fingers will bear upon the ends of the yoke directly opposite the knife edges 6 and 7, and the long fingers, 32—34, upon the ends of the adjusting arms 21—22. Thus with any adjustment of the tension of the springs 28 and 29 this ratio will obtain, so that the higher pressure for holding the 45 knife edges seated will be proportional to the amount of force required to oscillate the stylus lever. By making the stylus lever tensioning fingers 32—34 proportionately long, I not only get a reduction in tension, but an increased flexibility or amplitude of flexure, which while far in excess of that required by the very slight movement of the stylus lever, has the advantage of making the resistance offered throughout this movement 60 substantially constant as will be readily un-

derstood, thus overcoming the tendency to over-damp vibrations of higher amplitude, and giving a truer reproduction of the original sound.

In order to prevent stray vibrations of the sound box body from being communicated to the tone arm or other connection leading to the usual amplifying means, I provide a bushing 45 of rubber or equivalent sound insulating material within the sound box neck 75 4, which bushing is so proportioned as to fit snugly over the end of the tone arm. Communication between the diaphragm 8 and the interior of the neck 4 is had by an aperture 46 in the back wall of the sound box. 80

Some changes of detail, design, proportions and arrangement can be made herein without departing from my invention. I contemplate as my own any such changes as fall within the scope of the appended claims. 85

Having thus described my invention what I claim and desire to secure by Letters Patent is:

1. In a sound box, the combination of a diaphragm, a stylus lever connected thereto and carried by a transverse yoke mounted to oscillate on knife bearings, and resilient tensioning means arranged to bear on the yoke at points lying outside of the axis of said bearings and in a plane passing 90 through the stylus lever and its connection with the diaphragm and perpendicular to the said axis to tension said stylus lever in opposite directions, whereby the opposing forces exerted by the diaphragm and the 95 tensioning means respectively will act in a common plane perpendicular to the axis of oscillation.

2. In a sound box, the combination of a diaphragm, a stylus lever connected thereto and carried by a transverse yoke mounted to oscillate on knife edge bearings, a pair of tensioning arms carried by the yoke extending in opposite directions in the plane passing through the stylus lever and transverse 100 to the axis of said bearings, and resilient means acting on both the yoke and said arm to maintain the said bearings seated and to tension the stylus lever in opposite directions through said tensioning arms. 105

3. In a sound box, the combination of a diaphragm, a stylus lever connected thereto and carried by a transverse yoke mounted to oscillate on knife edge bearings, and resilient means bearing on said yoke at points 110 over said bearings to maintain the same seated and also at points spaced from the axis of said bearings in the plane of oscillation of the stylus lever, transverse to said axis to tension said stylus lever in opposite directions. 115

4. In a sound box, the combination of a diaphragm, a stylus lever connected thereto and carried by a transverse yoke mounted to oscillate on knife edge bearings, a pair of 120

tensioning arms carried by the yoke extending in opposite directions in the plane of the stylus lever and transverse to the axis of said bearings, and a pair of tensioning 5 springs each held fixed at a point intermediate its length and bearing at its opposite ends upon said yoke at a point opposite one of said bearings to maintain the same seated and at a point on one of said tensioning arms 10 to tend to oscillate the said yoke and stylus arm on the bearings.

5. In a sound box, the combination of a diaphragm, a stylus lever connected thereto and carried by a transverse yoke mounted 15 to oscillate on knife edge bearings, a pair of tensioning arms carried by the yoke extending in opposite directions in the plane

of the stylus lever and transverse to the axis of said bearings, and a pair of tensioning springs each held fixed at a point intermediate 20 its length and bearing at its opposite ends upon said yoke at a point opposite one of said bearings to maintain the same seated and at a point on one of said tensioning arms to tend to oscillate the said yoke and 25 stylus arm on the bearings, the point at which each of said springs is held fixed being so located with respect to the ends of the spring as to cause a greater pressure to be exerted upon the knife edge bearing than 30 upon the tensioning arm.

In testimony whereof I affix my signature.

JOSEF BRANDSTETTER.
